IMAGE TUBE

Leslie E. Flory and John E. Ruedy, Princeton,
N. J., and George A. Morton, Knoxville, Tenn.,
assignors to Radio Corporation of America, a
corporation of Delaware

Application October 5, 1946, Serial No. 701,588

5 Claims. (Cl. 250—165)

1

Our invention relates to an electrooptical image or viewing tube and more particularly to image tubes in which an electron image from a photocathode is electrostatically focused upon a fluorescent screen.

Image tubes of the electrostatically focused type have been made which have between a photocathode and a fluorescent screen a series of spaced annular anodes for focusing an electron image from the photocathode on a fluorescent screen. These tubes as heretofore made are rather bulky and not well adapted for use in portable equipment or for commercial production.

An object of the invention is to provide an improved image tube in which the image on the screen is reduced in size and is magnified by a lens to give a light image of greater brightness to the eye of the observer than would be the case if the image on the fluorescent screen were of the same size as the magnified image.

Another object of the invention is to provide an image tube in which the pin cushion effects are reduced by the shape of the optical lens through which the image is viewed.

Another object is to provide an image tube which is compact, mechanically strong, and suitable for manufacture on a commercial scale.

The novel features which we consider characteristics of our invention are set forth with particularity in the appended claims but for a better understanding of our invention itself both as to its organization and method of operation together with other and further objects and advantages reference may be had to the following description of a specific embodiment, shown merely for illustration, taken in connection with the accompanying drawing in which:

Fig. 1 is a diagrammatic longitudinal section of one form of embodiment of our invention;

Fig. 2 is a side view partly in longitudinal section showing various details of construction; and

Fig. 3 illustrates pin cushion effects and the correction thereof.

In accordance with our invention we provide an image tube of the electrostatically focused type, which forms on the target or fluorescent screen an image smaller than the optical image projected on the photocathode and in which the light image on the screen is viewed by the observer through a magnifying hemispherical lens mounted with its flat side substantially coincident with the plane of the screen. In the preferred construction we provide between the photocathode and the target a plurality of annular cylindrical anodes or focusing electrodes

2

which increase in length and preferably decrease in diameter progressively from the cathode to the target and are maintained at positive potentials which likewise increase progressively in the same direction. These annular anodes or focusing electrodes constitute in effect an electrostatic electron lens which produces a reduced and intensified electron image on the screen and thus produces a light image which is brighter and more intense the smaller the electron image. If this light image is magnified by viewing through a conventional eye piece type magnifier, there is no loss in brightness since the eye is the limiting aperture of the system and, consequently, to the observer there is a net gain in brightness inversely proportional to the ratio of areas of the original optical image on the photocathode and the reduced light image on the screen. The reduction in size of the light image and consequent increase in brightness is limited only by mechanical limitations in structure of the electron lens and by the degree of magnification which can conveniently be obtained in the eye piece.

The best shape of a photocathode for imaging the radiant energy thereon is a flat surface but the photocathode is usually made convex outwards to reduce the electrostatic effect which causes the sides of the image of a square to appear on the screen to be convex so that the image resembles a pin cushion. It has been impossible to entirely eliminate this effect by curving the photocathode without introducing equally objectionable photooptical defects. Therefore, a compromise has usually been made by curving the photocathode to partially eliminate pin cushion effect. In our invention we substantially complete the elimination of pin cushion effect by using a particular form of optical lens for magnifying the light image produced on the fluorescent screen by the photoelectrons. The lens constructed for this purpose is a hemisphere in form and it is mounted in the tube, with its flat side approximately coincident with the screen. The hemispherical lens tends to cause the sides of a square image to appear somewhat concave toward the center of the square, and thus corrects for the pin cushion distortion and may have, for example, a magnification of about 1.5. As a result a lower power eye piece type magnifier with a consequent greater aperture may be used in the eye piece through which the light image is observed.

Referring to the drawing, the tube envelope is preferably made in two sections of different diameters which are joined at their proximate

ends by an annular flange 2. For convenience in manufacture and to obtain a mechanically strong structure a plurality of leads, of which the two leads 3, 4 appear in the drawing, are sealed into the annular flange. The anodes or focusing electrodes 5, 6, 7 and 8 of the tube are mounted upon and carried by the leads in the flange and are mechanically tied together into a rigid structure by a plurality of insulating beads or spacers 9, 10 and 11. The transparent photocathode 12, which may be of the caesiated silver oxide type, for example, is mounted at and preferably formed on the transparent end wall of the larger section of the envelope remote from the annular flange, and the fluorescent screen or target 13 is placed at the end of the smaller section remote from the annular flange. The anode or focusing electrode 5, which is at the highest positive voltage, is preferably within the smaller section of the envelope and extends beyond the annular flange into the larger section. This construction facilitates the assembling of the anodes or focusing electrodes into a unitary mount on a stem consisting of the smaller section of the envelope with the annular flange 2, the edge of the annular flange then being sealed to the walls of the larger section of the envelope. By means of the leads in the annular flange 2 the photocathode and the focusing electrodes may be electrically connected to a source of voltage, such as a battery, as diagrammatically shown in Fig. 2.

The way our invention overcomes pin cushion effect may best be understood by reference to Fig. 3. The optical image of a square on the photocathode 12 is distorted so that it appears on the fluorescent screen to have concave sides A. A square image received through the hemispherical lens is distorted so that it appears to have convex sides B. These distortions are opposite and substantially equal in amount, so that the convex sides A appear to be straight, and the pin cushion effect is corrected so that the image appears square, as at C. Eye pieces or other lenses (not shown) are used to further magnify the image to the desired amount.

To produce a visible light image the screen may be of willemite or other phosphor which will fluoresce in response to electron bombardment. The photocathode may be made responsive to infra-red and near infra-red rays so that an image invisible to the eye may be transformed into a light image on the luminescent screen. The lens system for projecting on the photocathode an optical image of the object to be observed may be of glass for visible light or near infra-red, of quartz for ultra-violet light, or of some material such as hard rubber or rock salt for infra-red light.

In accordance with our invention the annular anodes or focusing electrodes coaxially aligned between the photocathode and the target progressively decrease in diameter and increase in length with their distance from the photocathode toward the target, and constitute an electrostatic condensing lens for the electron image produced by an optical image on the photocathode.

For best results the visible image on the fluorescent screen should be of about the same diameter as the hemispherical lens 14 through which the visible image on the screen 13 is viewed by the observer. The hemispherical lens may for convenience be made of glass and be integral with and constitute the end of the smaller section 2 of the envelope. The flat side

of the lens 14 faces the photocathode, and the screen 13 may be deposited on and be coextensive with the flat side of the lens 14. In one type of successful tube the photocathode 12 is about one and a half inches in diameter and the hemispherical lens 14 about one half inch in diameter. The electrostatic condensing lens focuses the electron image on the screen and reduces the focused image to about the diameter of the lens 14.

The invention is not limited to a tube of any particular dimensions but by way of example it may be stated that we have found it satisfactory to construct the tube with the following dimensions:

	Inches
Radius of curvature photocathode	2.38
Diameter of anode cylinder 8	1.30
Length of anode cylinder 8	.25
20 Diameter of anode cylinder 7	1.208
Length of anode cylinder 7	.500
Diameter of anode cylinder 6	1.103
Length of anode cylinder 6	.875
Diameter of opening 15	.725
25 Diameter of anode cylinder 5	.642
Length of anode cylinder 5	1.750
Gap between anodes 5 and 6	.125

The dimensions of the focusing anodes may be varied over relatively wide ranges, although in accordance with our invention these anodes should decrease in diameter and increase in length progressively from the photocathode to the target, and the approximate relationship of length to diameter above explained should be maintained for the best results.

As a number of possible embodiments may be made of our invention and changes may be made in the embodiment described, it is to be understood that while some illustrative forms of our invention have been described in considerable detail, our invention is not limited to such details, since many changes and modifications may well be made without departing from the spirit or scope of the invention in its broadest aspect.

What we claim as new is:

1. An image tube having a cylindrical envelope comprising two tubular coaxial sections of different diameters joined by a flange at their proximate ends, a photocathode at the other end of the larger section, a fluorescent screen at the other end of the smaller section, an electrostatic focusing lens between said photocathode and said screen comprising a plurality of tubular lens electrodes different progressively in increased length and decreased diameter with distance from said photocathode, the electrode of least length and greatest diameter being adjacent said photocathode and the lens electrode of greatest length and smallest diameter positioned in and concentric with the smaller section of said envelope with one end adjacent said screen and the other end projecting beyond the end of said smaller section and into the larger section of said envelope, and leads sealed into and extending through said flange and supporting said lens electrodes in said envelope.

2. An image tube comprising a cylindrical evacuated envelope having a transparent window at each end, a translucent photocathode adjacent one of said windows and adapted to produce in said envelope an electron image of an optical image on said window, a planar fluorescent screen adjoining said other window, a plurality of coaxial cylindrical tubular electrodes spaced along

said envelope in a row between said photocathode and said screen and constituting an electrostatic lens for focusing said electron image on said screen, an electrode of least length and greatest diameter being adjacent said photocathode and the length of each succeeding electrode being greater and its diameter less with increased distance from said photocathode.

3. An image tube comprising a curved photoelectric cathode for producing an electron image corresponding to an optical image on said photocathode, a plane fluorescent screen facing said photocathode, an electrostatic condensing lens between said photocathode and said screen for focusing said electron image on said screen with some pin cushion distortion to produce on said screen a correspondingly distorted visible image smaller than the optical image on said photocathode, and a hemispherical lens of substantially the diameter of said visible image adjoining said screen with its flat side substantially co-planar with said screen and producing an optical distortion substantially equal and opposite to the pin cushion distortion of the visible image on the screen.

4. An image tube comprising an envelope, a curved photoelectric cathode at one end of said envelope for producing an electron image corresponding to an optical image thereon, a glass hemispherical lens smaller than said photocathode sealed to the other end of said envelope with its flat side facing said photocathode, a fluorescent screen on and coextensive with the flat side

of said glass lens, and an electrostatic condensing lens between said photocathode and said screen for focusing said electron image reduced to the size of said screen and coextensive therewith.

5. An image tube having a cylindrical envelope comprising two tubular coaxial sections of different diameters joined at their proximate ends, a photosensitive cathode adjacent the other end of said larger section, the other end of said smaller section consisting of a glass hemispherical lens with its flat side facing said photosensitive cathode, a fluorescent screen on and coextensive with the flat side of said glass lens, and an electrostatic condensing lens comprising a plurality of spaced and coaxially aligned annular electrodes between said screen and said photosensitive cathode for producing on said screen a visible image coextensive with said screen.
